Fig. 8.

Fig. 7.

This application is a continuation of design applications D-5079, D-5080, D-5081 and D-5094, all filed Dec. 19, 1966 and now abandoned.

FIGS. 1 and 2 are perspective and end elevational views, respectively, of the sawhorse or similar article showing my new design;

FIGS. 3 and 4 are perspective and end elevational views, respectively, of a modified form thereof;

FIGS. 5 and 6 are perspective and end elevational views, respectively, of a further modified form thereof, and

FIGS. 7 and 8 are perspective and end elevational views respectively of a still further modified form thereof.

I claim:

The ornamental design for a sawhorse or similar article, as shown and described.
